Des. 209,326
Patented Nov. 21, 1967

209,326

WALL THERMOSTAT CASING

Alan E. Maire, Goshen, Ind., assignor to Robertshaw
Controls Company, Richmond, Va., a corporation of
Delaware

Filed July 13, 1966, Ser. No. 3,062

Term of patent 14 years

(Cl. D52—7)

FIG. 1.

FIG. 2.

FIG. 3.

FIG. 1 is a front elevational view of a wall thermostat casing embodying my new design;

FIG. 2 is a side elevational view of FIG. 1; and

FIG. 3 is a front perspective view of FIG. 1.

The rear of the thermostat casing is substantially plain in appearance.

The essential features of the design reside in the portions shown in full lines.

What is claimed is:

The ornamental design for a wall thermostat casing, substantially as shown and described.
